UNITED STATES PATENT OFFICE.

OTTO PETERMANN, OF GROTON, NEW YORK, ASSIGNOR TO CORONA TYPEWRITER COMPANY, INC., OF GROTON, NEW YORK, A CORPORATION OF NEW YORK.

TYPEWRITING MACHINE.

Application filed October 21, 1922. Serial No. 596,062.

To all whom it may concern:

Be it known that I, OTTO PETERMANN, a citizen of the United States, and resident of Groton, in the county of Tompkins and

5 State of New York, have invented certain new and useful Improvements in Typewriting Machines, of which the following is a specification.

This invention relates to improvements in 10 typewriting machines, and more particularly to improvements in ribbon mechanism for such machines.

Generally stated, the objects of the invention are to provide ribbon feeding and 15 reversing mechanism of simple construction which may be manufactured and assembled at small cost; to provide means for promptly and automatically reversing the direction of feed of the ribbon without injurious strain upon the ribbon; to provide a 20 ribbon-controlled but key-operated means for effecting the reversal of the ribbon feed; to provide simple and inexpensive means for supporting and driving the 25 ribbon spools.

The preferred construction of ribbon mechanism embodying the invention shown and described herein is illustrated in connection with the well-known Corona typewriting machine (model No. 3), and a further object of the invention is to provide an automatically reversing ribbon mechanism especially adapted for use on the aforesaid machine and which may be embodied therein at low cost and with a minimum of alteration of the construction and appearance of said machine.

In the accompanying drawings:

Figure 1 is a vertical sectional view of a 40 Corona machine provided with the improved ribbon mechanism, the parts being shown in positions occupied immediately before reversal of the feed to wind the ribbon on the right hand spool, said view being taken substantially centrally of the machine along a line extending from front to rear of the machine, and parts of the machine not necessary to a full understanding of the present invention being omitted;

Fig. 2 a view similar to Fig. 1 showing the operation of reversing the feed to wind the ribbon upon the right hand spool;

Fig. 3 a front view of the ribbon mecha-

nism, the parts being shown in the positions occupied thereby at the instant of reversal of the feed to wind the ribbon on the left hand spool;

Fig. 4 a fragmentary front view showing the parts in the positions occupied thereby in Fig. 2;

Fig. 5 a detail plan view, the positions of the parts of the reversing mechanism being the same as shown in Figs. 2 and 4;

Figs. 6 and 7 are detail perspective views of parts of the reversing mechanism adjacent the left and right hand spools, respectively, the parts being in the positions shown in Figs. 2, 4 and 5;

Fig. 8 a detail perspective view of the supporting means for the right hand spool and parts of the feeding and reversing means associated therewith;

Fig. 9 a perspective view of the bell-crank key-shifted reversing lever associated with the right hand spool;

Fig. 10 a front view (partly in section) of the bell-crank lever shown in Fig. 9 showing its pivotal connection with the bracket illustrated in Fig. 8;

Fig. 11 a bottom plan view showing the right hand end of the universal rocking frame and the hook device thereon for actuating the reversing lever associated with the right hand spool;

Fig. 12 a vertical fore and aft sectional view through the right hand ribbon spool, looking toward the left side of the machine, the parts being in the position shown in Fig. 1;

Fig. 13 a section on the line 13—13 of Fig. 12; and

Fig. 14 a side elevation of one of the spool and gear shifting yokes.

Referring to the parts by numerals, 1 designates the base or main frame part of the Corona machine before referred to, 2 designates the pair of vertically shiftable posts slidably held in the guide brackets 3 secured to the main frame part, 4 designates the pair of forwardly extending frame bars rigidly held to the upper ends of said posts and connected by the rod 5 at their rear ends, 6 designates the pair of folding arms pivotally held by pivot screws 37 at their forward ends to the forward ends of bars 4 and carrying the bed 7 for the traveling

platen carriage 8 at their rear ends, said arms 6 being foldable forwardly and downwardly to place the bed 7, carriage 8 and platen 9 in a compacted inverted position 5 over the keyboard. The posts 2 are connected at their lower ends by a rod 10 and are movable vertically by shift key levers (not shown) to elevate the arms 4, rod 5, and arms 6 and the parts carried thereby 10 to two different positions for printing middle and upper case characters.

The three rows of printing key levers 11 are pivotally supported intermediate their ends on different fulcrum rods 12 secured 15 to the main frame and are connected by push links 13 to type bars 14 held to a pivot wire 15 in a segment 16 secured to the rear wall of the main frame. Each printing key lever has a finger 17 underlying the trans- 20 verse member of a universal bar 18 which is substantially U-shape in plan view and has its side arms pivotally held intermediate their ends to the rear fulcrum rod 12. The space bar 19 is supported on a pair of 25 spacing levers 19 (one of which is shown in dotted lines) pivotally supported in the main frame by a pivot rod 20 and engaging under the universal bar at their rear ends. The key levers 11, spacing levers 19, and 30 the forward ends of the side arms of the universal bar are returned to normal position by springs 21 connected therewith and secured at their forward ends to a bracket 22 mounted in the main frame.

35 A pair of upstanding levers 23, connected at their upper ends by a cross-bar 24, are pivotally held intermediate their ends to guide brackets 3 by pivot screws 25 to rock fore and aft of the machine, and the lower 40 ends of said levers are connected by links 26 to the side arms of the universal bar. Levers 23 are provided with inwardly projecting lugs 27 at their upper ends engaging in vertical slots 28 in the side arms 29 of an 45 upstanding sheet metal universal rocking frame of substantially U-shape, said side arms being connected by an integral flat cross-bar 30 and being pivotally held at their lower ends to rod 10 to move vertically 50 therewith and swing thereabout fore and aft of the machine. When a printing key or the space-bar is depressed the universal bar is rocked upwardly and the upstanding universal rocking frame 29-30 is rocked rear- 55 wardly to cause a tappet 31 on cross-bar 30 of the rocking frame to actuate the escapement-dog rocker of the Corona machine (not shown) and to cause a lug 32 on said cross-bar to actuate the ribbon vibrator of said 60 machine, a part of which is shown at 33. The ribbon feed pawls 34 are pivotally held to ears 35 on said cross-bar 30 and the noses or free forward ends thereof are urged upwardly by springs 36 connected with the 65 pawls and fingers 30^a on bar 30. Said pawls

are arranged to act on the forward or return movement of the rocking frame to feed the ribbon.

The foregoing parts are all constructed and arranged as in the Corona machine referred to and the preferred new construction and arrangement of parts whereby the objects of the present invention are attained will now be described.

The inked ribbon 38 has attached thereto 75 adjacent its opposite ends eyelets or other suitable abutment devices 39 and has its ends secured by resilient split clamping sleeves 42 to the tubular barrels 40 of the ribbon spools 41, which, as shown, are provided with heads or flanges only at their upper ends. As the supports, the spool-rotating means for each spool 41, and the devices for reversing the direction of rotation of the spools associated with each spool 41, 80 are duplicates, a detailed description of the means for supporting, rotating, and reversing the direction of the rotation of the right hand spool only will be given.

A sheet metal bracket has its flat central portion 43 elongated fore and aft of the machine and seated on the top of the right hand folding arm 6. A pair of screws 44 passed through said central portion 43 and threaded into arm 6 serve to detachably hold the bracket to the arm. A cylindrical vertically disposed metal post 45 has its enlarged lower end welded to portion 43 of the bracket adjacent the forward end of said portion. The bracket is formed with a flat 100 horizontally disposed angular arm 46 extending outwardly and forwardly and provided at its forward end with a bearing aperture 47 in a transverse plane forward of the plane of the posts 45. The apertured forward end of arm 46 is preferably raised slightly above the plane of the main portion thereof as shown in Figs. 3 and 10.

Part 43 of the bracket is formed at its inner and outer edges with upturned ears 48 and 49 at the rear of post 45 provided with bearing apertures 50 in which a spool driving shaft 51 is journaled. A driving worm 52 is fixed on shaft 51 between ears 48 and 49 and a ratchet 53 is fixed on the inwardly projecting end of said shaft in position to be engaged by the adjacent feed pawl 34 when the machine is in normal operative or unfolded condition just as in said Corona machine. An arm 54 extends forwardly from ear 48, said arm being disposed edge-wise in a vertical plane and having a horizontal slot 55 therein open at its forward end.

Arm 54 and ear 49 are provided with horizontally disposed supporting lugs 56 and 57 arranged in a plane flush with the highest point of worm 52, lug 56 being located forward and inside of post 45 and lug 57 being located at the rear and outside of said post.

A spool cup 58, having an axial opening 59 through which the post extends, is provided with two downwardly punched bosses 60 seated on lugs 56 and 57 to support the bottom of the cup in a plane above the worm which is located therebeneath. An upward extension or cup-supporting lug 61 on ear 48 engages the bottom of the cup and assists in supporting the same. The cup is detachably held to lugs 56 and 57 by screws 62 having their heads countersunk in bosses 60.

The metal hub 63 of a driven worm gear 64 is slidably and rotatably mounted on the reduced upper portion of post 45. The lower end of hub 63 is adapted to seat on shoulder 65 on the post to support gear 64 in mesh with worm 52 and the upper end of the hub is adapted to move up and down in aperture 59 in the cup, said upper end of the hub being made sufficiently long to extend flush with or slightly above the bottom of cup 58 when the lower end of the hub is seated on shoulder 65. The gear hub 63 is formed with a reduced vertically split tubular extension 66 of resilient metal the two halves of which have a normally upwardly and outwardly divergent "set" to form a spool barrel supporting and retaining means or friction gripping post. The barrel 40 of spool 41 is forced downward over the beveled upper end of split post 66, compressing the divergent halves thereof, until its lower end seats on shoulder 67 at the upper end of the gear hub 63. The spool is thus readily detachable but is held by friction sufficiently tightly to prevent accidental rotary or endwise movements thereof relatively to the split post, so that the spool will revolve and move axially in unison with worm gear 64. The gear 64 is of greater diameter than the cup aperture 59 so that the gear and spool will not drop off the stationary guide post 45 when the machine is folded.

A U-shaped sheet metal gear-shifting yoke 68 has its side arms extending rearwardly at opposite sides of post 45 and pivotally held to the worm shaft 51 between the ends of worm 52 and the shaft-bearing ears 48 and 49. The front transverse bar of the sheet metal yoke 68 is provided with a raised portion or lug 69 midway its ends adapted to engage the under face of the worm gear 64 inside of its toothed perimeter and slide said gear and the ribbon spool axially upward to disconnect the gear 64 from worm 52.

Yoke 68 is operated by a sheet-metal bell-crank reversing lever having a transversely inwardly extending arm 70 located forward of post 45 and guided adjacent its inner end in slot 55 in bracket arm 54, and a rearwardly extending arm 71 located outside of bearing ear 49 and extending through a

guide slot 72 in an arm 73 extending outwardly from the bearing ear 49 on bracket 43. The reversing lever has a bearing or pivot stud 74 punched downward therefrom at the junction of arms 70 and 71 and held in the bearing aperture 47 in bracket arm 46 by a laterally bendable lug 75 turned up from the outer edge of the bracket arm and bent over the top face of the reversing lever closely adjacent the pivot stud. The arm 70 of the reversing lever is formed with a widened yoke-supporting portion 70^a underlying the inner side arm of yoke 68 and provided with a slot or aperture 76 through which a depending cam or lug 77, formed on the lower edge of the inner side arm of yoke 68, extends when arm 70 of the reversing lever is in its rearwardly shifted position. Lug 77 has a forwardly and downwardly inclined rear cam edge 77^a adapted to readily ride up over the rear edge of slot 76 when arm 70 of the reversing lever is swung forwardly.

Arm 70 of the reversing lever is formed at its inner end with a depending ear 78, disposed in a vertical plane extending transversely of the machine, and a sheet metal upstanding ribbon-operated trip lever 79 is pivotally held midway its ends to the front face of said ear by a screw 80. The lower end of lever 79 is normally held against a forwardly projecting stop lug 81 on ear 78 below pivot 80, by means of a weight 82 consisting of a metal block welded to the forwardly bent outer end of a short outwardly extending arm 83 on lever 79. This weight normally holds the lower end of lever 79 at the inner side of the path of movement of a forwardly and rearwardly movable sheet metal hook 84 carried by the universal rocking frame 29-30 so that the lever will not be engaged by the hook during rocking movements of said frame. A wire extension of lever 79 has its lower end slightly flattened and passed through superposed slots in the upper end of the lever and locked thereto against relative movement by hammering or pressing the interlocked parts to crimp the wire. The wire extension is doubled upon itself to form a ribbon guide loop 85 through which the ribbon 38 passes but through which the evelet 39 cannot pass. The rear ends of arms 71 of the bell-crank reversing levers are connected by a wire link 86 extending transversely of the machine above cross-bar 30 of the rocking frame and passing between the platen carriage 8 and the type-guide 87^a which in the Corona machine is secured to the carriage bed 7.

Hook 84 is bent midway its ends to provide a transversely extending portion 84^a disposed vertically edgewise so that it may be bent to adjust the forward end of the hook inward or outward. The rear flat portion 84^b of the hook is detachably held

against the under face of bar 30 by a screw 87 the shank of which passes through a short slot 88 extending longitudinally of the cross-bar and is screwed into part 84^b of the 5 hook. The screw 87 is adjustable along the slot to clamp part 84^b to cross-bar 30 with the outer edge of said part abutting against the flat inner face of side bar 29 of the rocking frame so as to prevent turning of the 10 hook about the screw.

At each depression of a printing key or the space-bar the universal bar 18 is rocked upward to rock the frame 29—30 rearwardly as shown in Fig. 2, and upon release 15 of said key or bar the frame returns to normal position as shown in Fig. 1, under the influence of the universal-bar return spring 21. Hooks 84 move rearwardly and forwardly normally without engaging the trip 20 levers, and pawls 34 rotate the ratchets part of a revolution on each return movement of the frame 29—30 thus partly rotating both worms 52 in the same direction. Assuming the left hand spool and gear to be lowered 25 and the right hand spool and gear to be elevated, owing to rearward swinging of arm 70 of the left-hand reversing lever and forward swinging of the arm 70 of the right hand lever by engagement of left hand hook 30 84 with left hand trip lever 79 (as shown in Fig. 3), it will be obvious that the ribbon will be wound upon the left hand spool during succeeding key strokes, passing from the rear of the right hand spool around in front 35 of the left hand spool which will be rotated in clockwise direction by its gear 64 and worm 52. The right hand spool and gear are held elevated by their shifter yoke 68 whose cam lug 77 is seated on top of part 70^a 40 of arm 70 of the reversing lever at the rear of slot 76, and whose lug 69 engages under and supports gear 64 of the right hand spool in elevated disconnected position, as shown in Figs. 3 and 12, so that said gear is free to 45 rotate in counter-clockwise direction.

As the ribbon becomes exhausted from the right hand spool the eyelet near the right hand end of the ribbon engages wire guide loop 85 on the right hand trip lever 79 and 50 rocks the lower end of the trip lever outward until it is in the path of the hook 84. On the next depression of a key or the space-bar the rearward movement of the frame 29—30 carries hooks 84 rearward and the 55 right hand hook 84 engages and pulls back the tripped lever and the arm 70 of the reversing lever upon which it is mounted, as shown in Fig. 2, causing the parts to assume the positions shown in Figs. 4 to 7. 60 The left hand yoke 68 is thus thrown upward to elevate the left hand gear 64 and its spool to disconnect said gear from the left hand worm 52, while the right hand yoke drops down onto its reversing lever as cam 65 lug 77 thereon drops through slot 76 and the

right hand gear and spool slide down their guide post 45 until the gear meshes with the right hand worm 52 with its hub on shoulder 65. Lug 69 and shoulder 65 are preferably of such height that lug 69 will not 70 engage gear 64 when the gear hub engages shoulder 65.

The movements of the reversing levers are limited by engagement of arms 70 with the rear ends of slots 55 and the link connection 75 86 between the levers. Excessive tilting of levers 79, especially in folding the machine, is prevented by engagement of weights 82 with the under side of arms 70 of the reversing levers. It will be observed 80 that the reversal of the driving connections takes place while the ribbon and gears and worms are stationary, that is, during the inactive rearward movement of feed pawls 34, and is accomplished by power applied to the 85 keys or space bar. The flange of the spool cup is above the lower edge of the ribbon even when the spool is raised and each cup flange is cut away at the inner side of the cup at 89 to permit free passage of the ribbon 90 to the guide loops 85 on the trip levers. A ribbon-retaining finger 90 is preferably provided on each cup flange extending up past the edge of the head of the spool 41.

It will be observed that all parts of the 95 ribbon-supporting, guiding, feeding, and reversing means, except pawls 34 and hooks 84, which are mounted on the rocking frame, fold with the platen carriage, and that operative connection is made and broken between the folding and non-folding parts 100 by simply moving the folding frame part of the Corona machine to or from extended normal operative position. The usual spring 105 detent fingers for ratchets 53 employed in the Corona machine are shown at 91 and are secured at their forward ends to the cup supports 56.

What I claim is:

1. In a typewriting machine, the combination 110 with an inking ribbon having abutments near its ends and a pair of spools with which the ends thereof are connected, of a pair of driven members connected with the spools to rotate and move axially therewith, a pair of stationary posts supporting 115 said spools and driven members for rotary and axial movements, a pair of driving members for rotating the driven members, means for simultaneously shifting the driven members axially in opposite directions to connect one driven member with its driving member and disconnect the other driven member from its driving member, a pair of normally inactive trip devices mounted on the 120 driven member shifting means and movable alternately by the abutments on the ribbon to active position, and universal key-operated means for engaging a shifted trip device to operate said driven member shifting 125 130

means to reverse the direction of feed of the ribbon.

2. In a ribbon feeding mechanism for writing machines, the combination with a pair of driving members and means for rotating the same at each printing operation of the machine, of a pair of driven members shiftable axially into and out of engagement with the driving members, a pair of ribbon spools connected to rotate with the driven members, an inking ribbon connected at its ends with the spools, abutments on said ribbon near each end thereof, reversing means for shifting the driven members axially simultaneously in opposite directions, universal key-operated means vibrating at the key-strokes, and normally inactive devices shiftable by said abutments alternately into the path of movement of said key-operated means and connected with the reversing means to actuate the same when either of said devices is moved by said key-operated means.

3. In a ribbon feeding mechanism for writing machines, the combination with a pair of driving members and means for rotating the same at each printing operation of the machine, of a pair of driven members shiftable axially into and out of engagement with the driving members, a pair of ribbon spools connected to rotate with the driven members, an inking ribbon connected at its ends with the spools, abutments on said ribbon near each end thereof, a pair of reversing levers pivotally supported to swing transversely of the axis of rotation of the driven members, a link connecting the levers, trip devices on the levers movable alternately into active position by the abutments on the ribbon, universal key-operated means adapted to engage the trip devices when in active position to swing the levers alternately in opposite directions, and means operable by the levers for shifting the driven members axially simultaneously in opposite directions.

4. In a ribbon feeding mechanism for writing machines, the combination with a pair of driving members and means for rotating the same at each printing operation of the machine, of a pair of driven members shiftable axially into and out of engagement with the driving members, a pair of ribbon spools connected to rotate with the driven members, an inking ribbon connected at its ends with the spools, abutments on said ribbon near each end thereof, a pair of reversing levers pivotally supported intermediate their ends to swing transversely of the axis of rotation of the driven members, a link connecting the levers at one end, universal key-operated means for rocking the levers, a pair of normally inactive trip devices pivotally mounted on the other ends of the levers and shiftable alternately by the abut-

ments on the ribbon into the path of movement of the universal key-operated means, and means operated by the levers for shifting the driven members axially simultaneously in opposite directions.

5. In a ribbon feeding mechanism for writing machines, the combination with a pair of driving members and means for rotating the same at each printing operation of the machine, of a pair of driven members shiftable axially into and out of engagement with the driving members, a pair of ribbon spools connected to rotate with the driven members, an inking ribbon connected at its ends with the spools, abutments on said ribbon near each end thereof, a pair of reversing levers pivotally supported intermediate their ends to swing transversely of the axis of rotation of the driven members, a link connecting the levers at one end, universal key-operated means for rocking the levers, a pair of normally inactive trip devices pivotally mounted on the other ends of the levers and shiftable alternately by the abutments on the ribbon into the path of movement of the universal key-operated means, and a pair of swinging members engaging the driven members to shift the same axially having cam surfaces engaged by the levers for moving the swinging members simultaneously in opposite directions.

6. In a typewriting machine, the combination of a pair of posts, means rigidly supporting said posts in upright position, a pair of spool cups, means detachably holding each of said cups to a part of the machine in upright position, each cup having a base plate provided with an aperture through which one of said posts extends, a pair of toothed rotary driving members arranged under the cups to rotate about the posts, a pair of resilient longitudinally divided tubular spool holders affixed to the driving members and surrounding the posts, a pair of ribbon spools frictionally held on said resilient holders, said holders and driving members being loosely mounted on the posts and said driving members being of larger diameter than the apertures in the base plates of the cups and cooperating with said base plates to prevent accidental disconnection of the spool holders and spools from the posts in handling the machine, and means for rotating the toothed driving members.

7. In a typewriting machine, the combination with an inking ribbon having abutments near its ends and a pair of spools with which the ends of the ribbon are connected, of a universal key-operated vibrating member, a pair of driving worms, shafts on which said worms are fixed, ratchets on said shafts, pawls on said key-operated member for rotating the ratchets, a pair of worm gears, reversing means operable by said key-operated member for shifting the worm gears

axially simultaneously in opposite directions to connect one worm gear with its driving worm and disconnect the other gear from its driving worm, stationary posts slidably and 5 rotatably supporting the worm gears, means for connecting the spools to rotate with the worm gears and more axially therewith, and means operable by the ribbon abutments for establishing operative connection between 10 the key-operated member and the reversing means.

8. In a typewriting machine, the combination with an inking ribbon having abutments near its ends and a pair of spools 15 with which the ends of the ribbon are connected, of a universal key-operated vibrating member, a pair of driving worms, shafts on which said worms are fixed, ratchets on said shafts, pawls on said key-operated 20 member for rotating the ratchets, a pair of worm gears, stationary posts supporting the worm gears for rotary and axial movements, means connecting the spools to move with the worm gears, a pair of reversing levers, 25 a link connecting said levers, a pair of swinging gear shifters having cam surfaces engaged by the reversing levers to shift the worm gears simultaneously in opposite directions, and trip devices shiftably mounted 30 on the reversing levers movable by the ribbon abutments alternately into the path of movement of said key-operated member.

9. In a typewriting machine, the combination of a folding platen carriage support, 35 a vertically movable case shift frame carrying said support, a pair of horizontally disposed brackets secured to the carriage support at their rear ends at opposite sides of the machine and provided with upstanding 40 cup-supporting lugs, a pair of spool-cups detachably held to said lugs above the brackets and having base plates provided with central apertures, a pair of vertical posts rigidly held at their lower ends to said 45 brackets and extending through the apertures in the base plates of the cups, a pair of horizontally disposed bell-crank reversing levers under the cups pivoted on the brackets to swing about vertical axes and 50 each having an arm extending fore and aft of the machine and an arm extending transversely of the machine, a transverse link connecting the fore-and-aft extending lever arms, a pair of tubular spool holders loosely 55 mounted on the posts, a pair of toothed rotary driving members located between the reversing levers and cups and fixed on the spool holders, said posts having shoulders supporting the driving members above the 60 levers and said members being of greater diameter than the apertures in the cup base plates, a pair of driving-member turning devices mounted on the brackets, universal key-operated means for actuating said devices 65 when the folding carriage support is

in normal position, a pair of upstanding ribbon-abutment operated trip devices pivoted on the transversely extending arms of the reversing levers to swing transversely of the machine from normal inactive positions to active positions, and means movable fore-and-aft of the machine with a part of said universal key-operated means for engaging a trip device shifted to active position and moving the same fore-and-aft of 75 the machine to simultaneously rock the reversing levers in opposite directions, each of said levers operating when moved in one direction to effect relative movement between the adjacent rotary driving member and its 80 turning device to operatively connect the same and operating when moved in the opposite direction to disconnect said member and device.

10. In a typewriting machine, the combination of a frame, a platen carriage mounted on the frame, brackets held to said frame forward of the carriage, upstanding posts on said brackets, worm shafts journaled in said brackets and extending transversely of the frame, worms on said shafts, ratchets on said shafts, worm gears slidably and rotatably mounted on the lower ends of said posts, upstanding spool-holding means carried by said gears, gear-shifting yokes 95 straddling the posts under the worm gears and pivotally held to the worm shafts, horizontally swinging bell-crank reversing levers pivotally held to said brackets having rearwardly extending arms and inwardly extending arms overhanging the frame, a link connecting the rearwardly extending lever arms, cams on the yokes engaged by the inwardly extending arms of the bell-crank levers to rock the yokes, upstanding trip levers pivotally held to the inwardly extending arms of the bell-crank levers to swing transversely of the frame, a forwardly and rearwardly swinging universal rocking member in the frame, pawls on said member 100 engaging the ratchets, a pair of hooks on said member normally movable fore and aft of the frame adjacent the trip levers without engaging the trip levers, spools on the spool-holding means, and a ribbon connected with the spools having abutments near its ends for swinging first one and then the other trip lever into the path of movement of its associated hook.

11. In a typewriting machine, the combination of printing keys, a pair of worms, means operable by the printing keys for turning said worms during the return or upward stroke only of each key, a pair of stationary posts supported at one side of the worms and extending transversely of the worms, a pair of worm gears slidably and rotatably mounted on the posts, a pair of spool holders affixed to said gears, a pair of ribbons spools on the holders, an inked rib-

- bon connected at its ends with said spools, reversing means operable by said key-operated means on the down stroke only of a printing key upon exhaustion of the ribbon 5 from either spool to shift the two worm gears together with the spool holders and spools thereon in opposite directions to carry the worm gear associated with the empty spool into mesh with the adjacent worm 10 and carry the other worm gear out of mesh with the other worm, and a pair of trip devices movable alternately by the ribbon into position to temporarily connect said reversing means with said key-operated means.
- 15 12. In an automatic direction-reversing feed mechanism for inked ribbons of typewriting machines, the combination of two driving worms, means for rotating said worms upon actuation of the keys of the 20 machine, two stationary posts mounted at one side of the worms and arranged transversely of the axes of the worms, two worm gears slidably and rotatably mounted on the posts, two axially arranged spool-holders 25 carried by the worm gears to slide and rotate therewith, two spools on the spool-holders, an inked ribbon connected at its ends to the spools, and ribbon-controlled means operable by a part of said driving 30 worm rotating means upon exhaustion of the ribbon from either spool to shift the worm gear associated with the empty spool along its supporting post into mesh with its driving worm and shifting the other worm gear 35 along its supporting post out of mesh with its driving worm.
13. In a typewriting machine, the combination of an upstanding rocking frame pivotally supported to swing fore-and-aft of 40 the machine, a pair of hooks held to said frame at opposite sides of the machine to move fore-and-aft therewith, printing key levers, a universal bar operable by said key levers and connected with the frame to rock 45 said frame, a pair of toothed rotary spool-driving members, a pair of ribbon spools driven by said members, a ribbon connected to said spools having abutments near its ends, a pair of driving member turning de- 50 vices operable by said rocking frame, a pair of horizontally disposed bell-crank levers pivotally supported to swing about vertical axes at opposite sides of the machine and each having an arm extending fore-and-aft 55 of the machine and an arm extending transversely of the machine, a transverse link connecting the fore-and-aft extending lever arms, and a pair of upstanding trip devices pivotally supported on the transverse 60 arms of the levers to swing transversely of the machine and each movable by one of the ribbon abutments from a normal position out of the path of the adjacent hook to a position in the path of said hook to effect 65 simultaneous swinging movements of the bell-crank levers in opposite directions, each of said levers operating when moved in one direction to effect relative movement between the adjacent driving member and its associated turning device to connect the same and operating when moved in the opposite direction to disconnect the driving member and turning device.
14. In a typewriting machine, the combination of an upstanding rocking frame 70 pivotally supported to swing fore and aft of the machine, a pair of hooks held to said frame at opposite sides of the machine to move fore-and-aft therewith, printing key levers, a universal bar operable by said key 75 levers and connected with the frame to rock said frame, a pair of toothed rotary spool-driving members, a pair of ribbon spools driven by said members, a ribbon connected to said spools having abutments near its 80 ends, a pair of driving-member turning devices operable by said rocking frame, a pair of horizontally disposed bell-crank levers pivotally supported to swing about vertical axes at opposite sides of the machine and each having an arm extending fore-and-aft of the machine and an arm extending transversely of the machine, a transverse link connecting the fore and aft extending lever arms, and a pair of upstanding trip devices 85 pivotally supported on the transverse arms of the levers to swing transversely of the machine and each movable by one of the ribbon abutments from a normal position out of the path of the adjacent hook to a position in the path of said hook to effect 90 simultaneous swinging movements of the bell-crank levers in opposite directions, each of the levers operating when moved in one direction to effect relative movement between the adjacent driving member and its associated turning device to connect the same and operating when moved in the opposite direction to disconnect the driving member and turning device.
15. In a typewriting machine, the combination of an upstanding rocking frame 95 pivotally supported to swing fore-and-aft of the machine, a pair of hooks held to said frame at opposite sides of the machine to move fore-and-aft therewith, printing key levers, a universal bar operable by said key 100 levers and connected with the frame to rock said frame, a pair of toothed rotary spool-driving members, a pair of ribbon spools driven by said members, a ribbon connected to said spools having abutments near its ends, a pair of driving member turning de- 105 vices operable by said rocking frame, a pair of horizontally disposed bell-crank levers pivotally supported to swing about vertical axes at opposite sides of the machine and each having an arm extending fore-and-aft of the machine and an arm extending transversely of the machine, a transverse link connecting the fore-and-aft extending lever arms, and a pair of upstanding trip devices 110 pivotally supported on the transverse arms of the levers to swing transversely of the machine and each movable by one of the ribbon abutments from a normal position out of the path of the adjacent hook to a position in the path of said hook to effect simultaneous swinging movements of the bell-crank levers in opposite directions, each of the levers operating when moved in one direction to effect relative movement between the adjacent driving member and its associated turning device to connect the same and operating when moved in the opposite direction to disconnect the driving member and turning device, said hooks being effective to move an active trip device only on the down stroke of a printing key and said turning devices operating to rotate the toothed driving members only on the upward strokes of the printing keys.
16. In a typewriting machine, the combination of an upstanding rocking frame 115 pivotally supported to swing fore-and-aft of the machine, a pair of hooks held to said frame at opposite sides of the machine to move fore-and-aft therewith, printing key levers, a universal bar operable by said key levers and connected with the frame to rock said frame, a pair of toothed rotary spool-driving members, a pair of ribbon spools driven by said members, a ribbon connected to said spools having abutments near its ends, a pair of driving-member turning devices operable by said rocking frame, a pair of horizontally disposed bell-crank levers 120 pivotally supported on the transverse arms of the levers to swing transversely of the machine and each movable by one of the ribbon abutments from a normal position out of the path of the adjacent hook to a position in the path of said hook to effect simultaneous swinging movements of the bell-crank levers in opposite directions, each of the levers operating when moved in one direction to effect relative movement between the adjacent driving member and its associated turning device to connect the same and operating when moved in the opposite direction to disconnect the driving member and turning device.
17. In a typewriting machine, the combination of an upstanding rocking frame 125 pivotally supported to swing fore-and-aft of the machine, a pair of hooks held to said frame at opposite sides of the machine to move fore-and-aft therewith, printing key levers, a universal bar operable by said key levers and connected with the frame to rock said frame, a pair of toothed rotary spool-driving members, a pair of ribbon spools driven by said members, a ribbon connected to said spools having abutments near its ends, a pair of driving-member turning devices operable by said rocking frame, a pair of horizontally disposed bell-crank levers 130 pivotally supported on the transverse arms of the levers to swing transversely of the machine and each movable by one of the ribbon abutments from a normal position out of the path of the adjacent hook to a position in the path of said hook to effect simultaneous swinging movements of the bell-crank levers in opposite directions, each of the levers operating when moved in one direction to effect relative movement between the adjacent driving member and its associated turning device to connect the same and operating when moved in the opposite direction to disconnect the driving member and turning device.

pivots supported to swing about vertical axes at opposite sides of the machine and each having an arm extending fore-and-aft of the machine and an arm extending transversely of the machine, a transverse link connecting the fore and aft extending lever arms, and a pair of upstanding trip devices pivots supported on the transverse arms of the levers to swing transversely of the machine and each movable by one of the ribbon abutments from a normal position out of the path of the adjacent hook to a position in the path of said hook to effect simultaneous swinging movements of the bell-crank levers in opposite directions, each of said levers operating when moved in one direction to effect relative movement between the adjacent driving member and its associated turning device to connect the same and operating when moved in the opposite direction to disconnect the driving member and turning device, said trip devices and said bell-crank levers being so arranged that swinging movement of each trip device about its pivot is limited in both directions by the bell-crank lever carrying the trip device.

16. In a typewriting machine, the combination of an upstanding rocking frame 30 pivotally supported to swing fore and aft of the machine, a pair of hooks held to said frame at opposite sides of the machine to move fore-and-aft therewith, printing key levers, a universal bar operable by said key 35 levers and connected with the frame to rock said frame, a pair of toothed rotary spool-driving members, a pair of ribbon spools driven by said members, a ribbon connected to said spools having abutments near its 40 ends, a pair of driving-member turning devices operable by said rocking frame, a pair of horizontally disposed bell-crank levers pivotally supported to swing about vertical axes at opposite sides of the machine and 45 each having an arm extending fore-and-aft of the machine and an arm extending transversely of the machine, a transverse link connecting the fore-and-aft extending lever arms, and a pair of upstanding trip devices 50 pivotally supported on the transverse arms of the levers to swing transversely of the machine and each movable by one of the ribbon abutments from a normal position out of the path of the adjacent hook to a 55 position in the path of said hook to effect simultaneous swinging movement of the bell-crank levers in opposite directions, each of said levers operating when moved in one direction to effect relative movement between the adjacent driving member and its 60 associated turning device to connect the same and operating when moved in the opposite direction to disconnect the driving member and turning device, said bell-crank levers 65 and trip devices having abutting portions

for arresting the trip devices in normal inactive position, and weights rigidly affixed to said trip devices for restoring the same to normal position after reversal of the ribbon feed.

17. In a typewriting machine, the combination of an upstanding rocking frame pivotally supported to swing fore-and-aft of the machine, a pair of hooks held to said frame at opposite sides of the machine to move fore-and-aft therewith, printing key levers, a universal bar operable by said key levers and connected with the frame to rock said frame, a pair of toothed rotary spool-driving members, a pair of ribbon spools driven by said members, a ribbon connected to said spools having abutments near its ends, a pair of driving-member turning devices operable by said rocking frame, a pair of horizontally disposed bell-crank levers pivotally supported to swing about vertical axes at opposite sides of the machine and each having an arm extending fore-and-aft of the machine and an arm extending transversely of the machine, a transverse link connecting the fore-and-aft extending lever arms, and a pair of upstanding trip devices pivotally supported on the transverse arms of the levers to swing transversely of the machine and each movable by one of the ribbon abutments from a normal position out of the path of the adjacent hook to a position in the path of said hook to effect simultaneous swinging movement of the bell-crank levers in opposite directions, each of said levers operating when moved in one direction to effect relative movement between the adjacent driving member and its associated turning device to connect the same and operating when moved in the opposite direction to disconnect the driving member and turning device, said bell-crank levers and trip devices having abutting portions for arresting the trip devices in normal inactive position, and weights rigidly affixed to said trip devices for restoring the same to normal position after reversal of the ribbon feed, said weights being arranged to engage the levers to limit movement of the trip devices away from normal position. 110

18. In a typewriting machine, the combination of an upstanding rocking frame pivotally supported to swing fore-and-aft of the machine, a pair of hooks held to said frame at opposite sides of the machine to move fore and aft therewith, printing key levers, a universal bar operable by said key levers and connected with the frame to rock said frame, a pair of toothed rotary spool-driving members, a pair of ribbon spools driven by said members, a ribbon connected to said spools having abutments near its ends, a pair of driving-member turning devices operable by said rocking frame, a pair of horizontally disposed bell-crank levers 120 125 130

5 pivotally supported to swing about vertical axes at opposite sides of the machine and each having an arm extending fore-and-aft of the machine and an arm extending trans-
 10 versely of the machine, a transverse link connecting the fore-and-aft extending lever arms, and a pair of upstanding trip devices pivotally supported on the transverse arms of the levers to swing transversely of the machine and each movable by one of the ribbon abutments from a normal position out of the path of the adjacent hook to a position in the path of said hook to effect simultaneous swinging movements of the 15 bell-crank levers in opposite directions, and cam means operable by each lever to effect operative disconnection of the adjacent driving member and turning device or permit operative connection thereof.

20 19. In a typewriting machine, the combination of a main frame, a platen carriage support shiftable up and down to change case, a pair of brackets held to said support at their rear ends at opposite sides of the 25 machine, a pair of upstanding spool holders, a pair of horizontally disposed toothed rotary driving members affixed to said holders and rotatably mounted on the brackets, a pair of ribbon spools held to said holders to 30 rotate therewith, a pair of bell-crank levers pivotally held to the brackets to swing horizontally and each having an arm extending fore and aft of the machine and an arm extending transversely of the machine, a trans-
 35 verse link connecting the fore-and-aft extending lever arms, a key-operated rocking frame pivotally supported to swing fore-and-aft of the machine, a pair of driving-member turning devices mounted on the brackets 40 and both operatively connected with and simultaneously operable by said rocking frame in all case positions of the platen carriage support for turning the driving members, a pair of hooks extending fore and aft 45 of the machine at opposite sides thereof and carried by said rocking frame, a pair of upstanding trip devices pivotally supported on the transverse lever arms to swing transversely of the machine, each of said trip devices having a ribbon guide at its upper end 50 adapted to be engaged by a ribbon abutment and having a depending arm arranged to be engaged by and moved an equal distance in a general fore-and-aft direction by the adjacent hook in all case positions of the 55 carriage support when the device is rocked by a ribbon abutment, said levers operating upon movement of a trip device by a hook to operatively disconnect one turning device and its associated driving member and operatively connect the other turning device and its associated driving member.

20. In a typewriting machine, the combination of a shiftable platen carriage support for changing the normal relation between 60 the types and platen, a pair of ribbon spools rotatably mounted on the support, a pair of trip devices provided with ribbon guiding portions adapted to be engaged by ribbon abutments to shift the trip devices trans-
 65 versely of the machine alternately from inactive to active position, a pair of reversing levers pivotally mounted on the support and upon each of which one of the trip devices is shiftably supported to move transversely 70 of the machine, a link connecting the reversing levers, a universal bar on the main frame of the machine, means forming interruptible driving connections between the universal bar and said spools in all case positions of 75 the support for rotating the spools, and means operable by said universal bar for engaging an active trip device and moving the same fore-and-aft of the machine in all case 80 positions of the support, said levers operating upon movement of a trip device by the universal bar to interrupt the driving connection between the universal bar and a full spool and establish a driving connection between the universal bar and an empty spool. 85 90

In testimony whereof I hereunto affix my signature.

OTTO PETERMANN.
